UNITED STATES PATENT OFFICE.

RILEY A. SHAFFER, OF BELLEFONTAINE, OHIO.

BIT.

SPECIFICATION forming part of Letters Patent No. 693,914, dated February 25, 1902.

Application filed June 27, 1901. Serial No. 66,217. (No model.)

To all whom it may concern:

Be it known that I, RILEY A. SHAFFER, a citizen of the United States, residing at Bellefontaine, in the State of Ohio, have invented ; certain new and useful Improvements in Bits; and I do declare the following to be a full, clear, and exact description of the invention, such as will enable others skilled in the art to which it appertains to make and use the 10 same, reference being had to the accompanying drawings, and to the figures of reference marked thereon, which form a part of this specification.

My invention relates to improvements in 15 bits, and particularly to improvements in counterboring-bits. Its object is to form a bit whereby the bore and counterbore are made at the same operation.

A further object is to provide a counterboring-bit with means to regulate the depth 20 of the hole bored.

A further object is to form a counterboring tool wherein the bits are adjustable relative to each other.

25 A further object is to provide means whereby both bits will be clamped in the socket by a single operation.

With these and other objects in view my invention is hereinafter described and is illustrated in the accompanying drawings, in 30 which—

Figure 1 is a longitudinal section. Fig. 2 is a cross-section on line 2 2 of Fig. 1. Fig. 3 is a cross-section on line 3 3 of Fig. 1.

35 Referring more specifically to the drawings, the stock of the bit is indicated at 6, the bore-bit at 7, and the counterbore-bit at 8. The bit 8 is longitudinally bored to receive the bit 7, which is longitudinally adjustable 40 therein. In the stock 6 is a beveled screw-threaded socket 6^a, adapted to receive the exteriorly-screw-threaded shank 8^a of the bit 8, and centrally of the socket 6^a is a deeper socket 6^b, adapted to receive the shank 7^a of

45 the bit 7. Loosely mounted upon the stock is a sleeve 9, within which the stock may revolve. The sleeve is adjustably retained upon the stock between collars 10 and 10^a, mounted upon the stock and capable of being secured thereto by set-screws 11. The lower collar 10^a is located within the sleeve in a recess formed by an outwardly-offset portion 9^a

of the sleeve. The lower end of the sleeve extends below the stock and is adapted to form an adjustable stop to regulate the depth 55 of the hole by contact with the work. The sleeve also forms a convenient handpiece when the bits are being driven.

The shank 8^a of the counterbore-bit is longitudinally split, as indicated at 8^b, whereby 60 it is adapted to contract and bind the shank 7^a of the bit 7. When the bits are set in position according to the depth of bore and counterbore desired, the bit 8 is screwed in, and the beveled socket causes the split shank to 65 contract and tightly bind the shank of the inner bit 7.

It will be seen that the bits have relative longitudinal adjustment according to the depth of bore and counterbore desired; also, 70 that both bits are clamped in the socket at a single operation.

Having thus described the invention, what is claimed as new, and desired to be secured by Letters Patent, is—

75 1. In combination, a stock, bore and counterbore bits held therein, said bits having longitudinal adjustment relative to each other, and a sleeve upon the stock which is rotatable within the sleeve.

80 2. In combination, a stock, bore and counterbore bits held therein, said bits having longitudinal adjustment relative to each other, a sleeve within which the stock is rotatably mounted, said sleeve having longitudinal adjustment upon the stock.

85 3. In combination, a stock, a beveled socket in the stock, a counterbore-bit whose shank is adapted to engage said beveled socket, a main bore-bit, and a socket to receive the shank thereof.

90 4. In combination, a stock, a bore-bit, a counterbore-bit having a beveled screw-threaded shank, and a beveled screw-threaded socket in the stock adapted to receive said shank.

95 5. In combination, a stock, a counterbore-bit having a beveled split shank, a main bore-bit extending longitudinally and centrally within the counterbore-bit and adapted to be 100 clamped by the said shank, and a beveled socket in the stock adapted to receive said shank.

6. In combination, a stock, a bore-bit, a

counterbore-bit having a beveled, screw-threaded shank, and a beveled screw-threaded socket in the stock adapted to receive said shank.

5 7. In combination, a stock, a screw-threaded beveled socket, and a guide-socket, therein, a main bore-bit having a shank adapted to enter the guide-socket, a counterbore-bit having a beveled, screw-threaded split shank
10 adapted to enter the screw-threaded socket and to bind the shank of the main bore-bit.

8. In combination, a stock, adjustable collars thereon, a revoluble sleeve upon the

stock, adjustably held between the collars, a socket in the stock, and a bit held in the 15 socket.

9. In combination, a stock, a relatively revoluble sleeve thereon, longitudinally-adjustable collars upon the stock to retain the sleeve, the lower portion of the sleeve being 20 offset outwardly outside of and below the lower collar, and a bit held in stock.
